UNITED STATES PATENT OFFICE.

OSCAR W. MOORE, OF CHICAGO, ILLINOIS, ASSIGNOR TO THE NORLIPP COMPANY, OF CHICAGO, ILLINOIS, A CORPORATION OF ILLINOIS.

DESIGN FOR A COMBINED CIGARETTE DISPENSER AND HUMIDOR.

Application filed May 14, 1928. Serial No. 26,658. Term of patent 3½ years.

To all whom it may concern:

Be it known that I, OSCAR W. MOORE, a citizen of the United States, residing at Chicago, in the county of Cook and State of Illinois, have invented a new, original, and ornamental Design for a Combined Cigarette Dispenser and Humidor, of which the following is a specification, reference being had to the accompanying drawing, forming part thereof.

Fig. 2 is an end view of the same.

I claim:

The ornamental design for a combined cigarette dispenser and humidor as shown.

OSCAR W. MOORE.
